ELECTRIC METER OR SIMILAR ARTICLE

Henry C. Littlejohn, Lexington, Mass., assignor to General Radio Company, Cambridge, Mass., a corporation of Massachusetts

Application June 11, 1958, Serial No. 51,305

Term of patent 14 years

(Cl. D26—1)

FIG.1

FIG.2

FIG.3

Fig. 1 is a perspective view of an electric meter or similar article, showing my new design;

Fig. 2 is a front elevational view, the rear being conventional; and

Fig. 3 is a side elevational view, the opposite side being substantially a mirror image thereof.

What is claimed is:

The ornamental design for an electric meter or similar article, substantially as shown and described.
